KEYBOARDS FOR MUSICAL INSTRUMENTS
Donald J. Winch, 255 W. 34th St., New York, N.Y.
Filed Apr. 29, 1964, Ser. No. 363,551
5 Claims. (Cl. 84—423)

This invention relates to a keyboard construction for a musical instrument such as an organ or an accordion.

As is well understood, the operation of keys in such an instrument uncovers reed slots so that tones are generated as air is forced therethrough.

The construction of a keyboard of the above type has been complex and has further often resulted in repair difficulties. With the foregoing in mind I have devised a keyboard construction of extreme simplicity but with positive and controlled action which is most reliable, and with a minimum of moving parts so as to minimize later accidental displacement or the like. Further, my invention eliminates the necessity of providing spacers or guide rails between the keys. A further advantage of my construction is that the musical instrument can be made to be of very light weight.

I achieve the above objectives by cementing all the keys, in properly spaced relationship, on a relatively thin, rubber mounting strip, the mounting strip being disposed somewhat forwardly under each key so that it makes possible a form of see-saw action, the hammer at the rear end of the key rising as the finger end is depressed, and the hammer becoming automatically restored to slot closing position when pressure on the finger end is released.

Accordingly, by the simple expedient of cementing the keys to a sufficiently wide yet thin rubber base, I secure the required action without the necessity of employing any other return spring means or the like, while nevertheless maintaining each key precisely in place without any additional holding or guiding devices.

It will also be observed hereinafter that I have simplified the construction of the keys in that the white keys comprise straight strips with no special configuration as is generally required in keyboards.

The invention will be further understood from the following description and drawings wherein;

FIGURE 1 is a top plan view, partly broken away, of the keyboard of this invention;

FIGURE 2 is an enlarged cross-sectional view as taken along the line 2—2 of FIGURE 1;

FIGURE 3 is a view similar to FIGURE 2 but illustrating the key action; and

FIGURE 4 is an enlarged cross-sectional view as taken substantially along the lines 4—4 of FIGURE 1.

The keyboard is mounted on rigid supporting structure 10 which may be of wood or the like. Support structure 10 will normally rest upon a conventional bellows or other air flow generating apparatus. In accordance therewith the structure 10 includes an elongated platform 11 in which are formed the usual aligned reed slots 12. A number of reeds 13, for example representing a number of octaves, are mounted on the underside of platform 11, all in conventional manner, such mounting not being included in this invention.

The keyboard of this invention is mounted on the supporting structure 10 above the outlet of the reed slots 12. The top surface of structure 10 is provided with an elongated sponge rubber strip 14, cemented across structure 10 from one side of the instrument to the other. The function of resilient sponge rubber strip 14 is most important to this invention. It serves as a mounting and as a fulcrum for the lever action of the keys as will hereinafter be made clear. Such keys, in one particular form, may be about 7", or almost to scale as representa-

2

tive in FIGURE 3 hereof. In such an embodiment, the width of strip 14 was 1 $\frac{3}{8}$ ", and its thickness $\frac{1}{16}$ ". Thus, the width of strip 14 was about 25 percent of the length of the keys while its thickness was about 4 percent of its width. As will be shown hereinafter, these dimensions are important to the required action.

The keys 15 are elongated and aligned side-by-side as usual, the number, of course, depending upon the number of reeds and octaves. Such keys may be of wood or of 10 any suitable plastic material. They comprise narrow bodies approximately $\frac{5}{32}$ " wide, although this dimension is not of importance. Their mounting to rubber strip 14 is extremely simple yet effective. I simply cement the underside of the keys, in properly spaced relationship to 15 the rubber strip 14. Any conventional type of cement or glue may be used, I having found that what is commonly referred to as instant, contact, rubber-type cement is suitable.

As will be observed in FIGURE 2, the keys are mounted 20 on strip 14 so that the strip 14 is not precisely in the center of the key but is offset forwardly of such center. In other words, the rear, uncemented end of the key is longer than the front uncemented end by about 40 percent. This provides an efficient leverage action as will 25 be hereinafter explained. As for the construction of the keys 15, it will be observed that they are provided with a flat, widened metal base 16 cemented thereto to effectively form a rear hammer end which normally closes the slots 12. Further, a conventional chamois layer 17 is 30 provided over the reed slot platform 11, the chamois having openings corresponding with the slots 12, all as well understood, and to which I make no claim.

Successive keys 15, in proper order as is well understood, are provided with a raised finger portion 20, which 35 may be integral with the key, as desired. These raised finger portion keys may be referred to as the black keys. Between such black keys, the finger portions 20 are omitted and in their place is substituted a white plastic rectangular strip 20a cemented on a key at a lower level than finger 40 portion 20, these keys constituting the white keys.

Side frames 21 are mounted at the respective side edges of support structure 10 and a hand supporting platform 22 which extends across the entire width of the instrument is mounted on the side frames 21. Platform 22 may 45 be of smooth plastic and its front edge 23 is turned down and rests upon the keys at about the center thereof, although this particular resting point is not of importance.

The player's hands will rest upon platform 22 as illustrated in FIGURE 3 while his fingers will press on the 50 forward portions of the black keys or the white keys so as to uncover the reed slots.

The basic action of my keyboard is illustrated in FIGURE 3. It will be observed that as the player depresses the forward portion of key 15 (shown in FIGURE 3 as a 55 white key) the rubber strip 14 will become compressed at its front edge and will correspondingly tend to expand at its rear edge, although this action is somewhat minute and observable only upon careful inspection. A front rubber strip 24 serves as a cushion.

As the key 15 is depressed the rearwardly disposed 60 reed slot 12 is of course uncovered as is well understood, so that air under pressure will flow through the reed slot, causing the reed 13 to vibrate and generate a desired tone. The sponge rubber strip 14 automatically functions as a 65 return device since it will tend to restore itself to the normal uncompressed or unexpanded position shown in FIGURE 2. Thus the key will return to a normally planar position where it overlies strip 14 in a parallel relationship.

The above action is very simple yet effective. The stated 70 relative width of sponge rubber strip 14 is important in providing a controlled uncovering of the reed slots as

well as a precise return action. All this is accomplished by simply cementing the keys in spaced relationship on the sponge rubber strip and without requiring any other apparatus, the keys and the rubber strip being thereby rendered substantially unitary for positive and controlled action without likelihood of accidental displacement.

A further advantage of the foregoing structure is that the white key strips 20a have completely straight sides and can be very easily produced from continuous plastic strips without requiring the indented conformations as generally found on the keyboards of accordions and pianos.

Thus the instrument as above described is of pronounced simplicity in manufacture and operation while being at least as effective as the more complex structures now in use.

I have shown a preferred embodiment of my invention but it is obvious that numerous changes and omissions may be made therein without departing from its spirit.

What is claimed is:

1. In an air operated musical instrument having a series of reed slots which are normally covered, a keyboard therefor, said keyboard comprising a series of elongated keys aligned side-by-side, and a flat key supporting strip disposed under said keys, said strip being of resilient material, all of said keys being directly cemented to said strip so as to be substantially unitary therewith, said strip being disposed substantially forwardly of the center of each key so as to normally urge and bias the forward end of said keys upwardly whereby the rear end of said keys may function to normally cover said reed slots and whereby downward manual pressure on said forward ends will serve to uncover said slots.

2. A musical instrument keyboard according to claim 1 and wherein said strip is of a width approximately 25 percent of the length of said keys, said keys lying across said strip width with a greater part of said strip width being forward of said key center.

3. A musical instrument keyboard according to claim 2 and wherein the thickness of said strip is approximately 4 percent of the width of said strip, the rear, uncemented end of each key being longer than the front uncemented end thereof by approximately 40 percent, and a rigid support for the underside of said flat strip.

4. A musical instrument keyboard according to claim 3 and wherein each of said keys comprises a narrow body the underside of which is cemented to the top surface of said flat strip, a raised finger portion formed at the top front end of some of said keys, and flat, straight rectangular strips connected to the rest of said keys so that the keyboard presents successive and adjoining raised finger portion keys and flat rectangular strip keys.

5. A musical instrument keyboard comprising a series of elongated keys aligned side-by-side, a key supporting strip disposed across said keyboard and under said keys, said strip being flat and of sponge rubber, and all of said keys being cemented across the top surface of said strip with the center line across the width of said strip being forward of the center line of the length of each key whereby the resilience of said sponge rubber strip normally biases the forward end of said keys upwardly, a rigid support for the underside of said strip, said strip being of a width approximately 25 percent of the length of each key and the normal thickness of said strip being approximately 4 percent of the width of the strip.
